UNITED STATES PATENT OFFICE.

WALLACE BYRNE RUSSELL, OF CHICAGO, ILLINOIS.

THERAPEUTIC DEVICE.

1,073,525.

Specification of Letters Patent. Patented Sept. 16, 1913.

Application filed January 13, 1913. Serial No. 741,819.

To all whom it may concern:

Be it known that I, WALLACE BYRNE RUSSELL, citizen of the United States, residing at Chicago, in the county of Cook and State 5 of Illinois, have invented certain new and useful Improvements in Therapeutic Devices; and I do declare the following to be a full, clear, and exact description of the invention, such as will enable others skilled 10 in the art to which it appertains to make and use the same.

This invention relates to improvements in therapeutic devices.

One object of the invention is to provide 15 a therapeutic device adapted to be quickly and easily applied to the male organ of generation whereby the erection of this organ may be effected when the same from malformation or other cause has lost the power 20 of natural erection and which, by repeated use, will eventually restore the natural erectile power to the organ.

Another object is to provide a device of 25 this character having adjustable means for regulating the pressure of the device on the parts of the organ and to apply the pressure to the proper places for accomplishing the desired results.

With these and other objects in view, the 30 invention consists of certain novel features of construction, and the combination and arrangement of parts as will be more fully described and claimed.

In the accompanying drawings, Figure 1 35 is a perspective view of my improved therapeutic device; Fig. 2 is a vertical sectional view thereof showing in full and dotted lines the manner in which the same is opened and closed. Fig. 3 is a horizontal 40 sectional view of the device taken on the line 3—3 of Fig. 2.

My improved therapeutic device comprises a frame in the form of a circular body or ring 1 of suitable size and which may 45 be constructed of any suitable material. In the present instance the body 1 is shown as being constructed from two tubular hollow substantially semi-circular sections 2 and 3 which are substantially square or rectangular in cross section but have their corners and outer edges slightly rounded as shown. The ends of the sections 2 and 3 of the frame body 1 are closed in any suitable manner. The sections 2 and 3 are hingedly 50 connected at the outer corners of their engaging lower ends as shown at 4 to permit

said sections to be opened or swung apart when applying or removing the same. The main portion of the upper ends of the sections 2 and 3 are spaced apart a slight 60 distance to form between said ends a recess 5. The outer wall of the section 2 of the ring is extended to form a spacing lug 6, the outer end of which engages the adjacent end of the section 3 of the ring and 65 closes the outer end of the space or recess 5 between the ends of the sections 2 and 3. The sections 2 and 3 are securely fastened when in closed position by a spring catch 7 secured at its inner end to the outer side of 70 the free end of the section 3 of the frame. The catch 7 is in the form of a spring metal plate on the outer end of which is an inwardly projecting stud 8. The outer side of the lug 6 is slightly beveled on its end 75 and has therein a recess 9 with which the stud on the catch plate 7 springs into engagement when the sections of the ring are closed.

Arranged in the upper portion of the 80 ring or body 1 are compression plates 10 the lower portions of which are secured at their lower ends to the inner sides of the sections 2 and 3 of the ring, said lower portions of the plates extending inwardly 85 or toward each other on a slight curve as shown. The inner ends of the lower portions of the plates 10 are bent upwardly at points in line with the upper ends of the sections 2 and 3 of the frame as shown at 90 11, and said upwardly bent ends of the plates are secured in any suitable manner to the lower or inner corners of the spaced upper ends of the sections 2 and 3 of the ring as shown. The upwardly bent inner 95 ends of the plates 10 space the latter from the inner sides of the ring and hold the plates in position to form a compress or to exert a pressure at the proper places on the upper side of the organ when the device is 100 applied thereto and the organ forced upwardly by an adjustable pressure mechanism now to be described.

The adjustable pressure mechanism referred to comprises an organ engaging member 12 which is here shown as an open frame comprising a flat horizontally disposed base plate 13 to which is secured an upwardly projecting arched or bowed pressure applying plate 14. The base plate 13 has a swivelled connection near one end with the upper end of an adjusting and pressure regulat- 110

ing screw 15 which has a threaded engagement with a screw hole 16 in the hinged end of the section 2 of the ring or body 1. The member 12 is guided in its adjustment by the screw 15 and is positively held against turning with said screw by a guide bar 17, which is rigidly secured at its upper end to one end of the member 12 and has a sliding engagement with a slot 18 formed in the hinged end of the section 2 of the ring 1 adjacent to the screw hole 16 as clearly shown in Fig. 2 of the drawings.

In the use of the device the sections 2 and 3 are swung apart on their hinged connection, after first releasing the catch 7, thus permitting the device to be readily engaged with the organ. After the open sections of the ring have been placed in position on the organ, they are closed and fastened by the spring catch. When the sections 2 and 3 are thus fastened, the screw 15 is turned in the proper direction for moving the member 12 inwardly thus engaging the arched plate 14 with the lower side of the organ and forcing the latter upwardly into pressing engagement with the plates 10. The pressing action of the plates 10 at the proper places on the organ tends to restrict the return or circulation of blood in the organ which causes the erection of the latter. As the erection and enlargement of the organ proceeds, the screw 15 is turned in the proper direction for moving the member 12 outwardly so that pain or discomfort which would result from too much pressure is obviated. If desired the parts of the device which come into contact with the organ may be covered or inclosed in casings of rubber, chamois skin or the like, (not shown).

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. A therapeutic device of the character described comprising a frame formed in hingedly connected semi-circular sections, a catch to hold said sections in closed position, pressure plates fixed to the inner sides of the upper ends of said sections, an adjusting screw having a threaded engagement with the lower end of one of the sections of

the frame, a plate swiveled on the inner end of said screw, and a guide bar fixed at its inner end to said plate and having a sliding engagement with one of the sections.

2. A therapeutic device of the character described comprising a frame formed in hingedly connected sections, an automatically closing catch to hold said sections in closed position, pressure plates arranged in the upper portions of said sections in position to engage and impart pressure at the proper places to the organ with which the device is engaged and an adjustable pressure applying mechanism to force the organ into engagement with said plates.

3. A therapeutic device of the character described comprising a circular frame formed in sections hingedly connected at one end, a spacing lug on the free end of one of said sections and adapted to engage the adjacent end of the opposing section whereby said ends are spaced apart, a spring catch to hold said sections in closed and operative position, pressure plates arranged in the upper portions of said sections in position to properly engage the organ to which the device is applied, and an adjustable pressure applying mechanism to force the organ into engagement with said plates.

4. A therapeutic device of the character described comprising a frame formed in hingedly connected sections having their free ends spaced apart, an automatically engaging catch to hold said sections in closed position, pressure plates fixed to and spaced from the inner sides of the upper ends of said sections in position to properly engage the organ to which the device is applied, an adjustable pressure applying device comprising an adjusting screw having a threaded engagement with one of the sections of the frame, at the opposite ends thereof from said fixed pressure plates, an organ engaging member having a swiveled engagement with the inner end of said screw whereby said plate is adjusted to force the organ into engagement with said fixed pressure plates, and a guide bar fixed at its inner end to said organ engaging member and having a sliding engagement with one of the sections of the frame whereby said organ engaging member is guided and held against turning with said screw.

In testimony whereof I have hereunto set my hand in presence of two subscribing witnesses.

WALLACE BYRNE RUSSELL.
